CLASP

Joseph E. Kraft, Bronx, and Johanna Bergner, New York, N. Y., assignors to Universal Cover Fastener Company, Inc., New York, N. Y., a corporation of New York

Application May 26, 1939, Serial No. 275,890

6 Claims. (Cl. 24—248)

This invention relates to clasps suitable for securing fabrics and has for an object the provision of improvements in this art.

The invention has been developed for holding bed covers for infants but is suitable for holding all kinds of flexible sheet-like fabrics. It provides a new and improved clasp which may be very easily manipulated; which will very securely hold the fabrics in position; which is of a simple and sturdy construction; and which will be relatively inexpensive to manufacture.

One of the important features of the clasp is that it has its parts permanently assembled in such a way that it is not necessary to assemble them when attaching to a fabric article since they are always ready for clasping and unclasping and this may be accomplished by a simple movement by one hand, leaving the other hand entirely free to manipulate the article.

A preferred embodiment of the invention is shown in the accompanying drawing, wherein:

Fig. 1 is a top plan view of the clasp in open position;

Fig. 2 is a side view of Fig. 1;

Fig. 3 is a top plan view of the clasp in closed position; and

Fig. 4 is a side view of Fig. 3.

The clasp comprises a body part 10 and a toggle part 11 operatively associated with the body part.

The body part comprises a member 10 which may be formed of stiff wire having approximately straight parallel side bars 10a, a first jaw member in the shape of a fabric receiving loop or mouth 10b, and reversely bent attaching ends 10c. The plane of the loop 10b stands at approximately right angles to the side bars 10a. The bent attaching ends 10c are inclined at an angle of approximately 45 degrees to the side bars. The loop 10b is preferably bent downwardly sufficient to take the end of the toggle member, while the ends 10c are bent upwardly to some extent.

The toggle part 11 may be formed of a plate 11a and a cooperating tongue 11b, preferably formed of stiff wire. The tongue constitutes a second fabric gripping jaw.

The plate 11a of the toggle part is formed with curled ends, the lower one 11c, embracing the inturned ends 11d of the tongue, and the upper one 11e embracing the out-turned ends 10c of the body member. The upper curled end is cut away at the center, as shown at 11f, to receive the ends 10c of the body member. The plate 11a is preferably tapered on the sides, being

widest at its upper end, and these tapered sides form a stop by coming against the inside edges of the body bars 10a when the clasp is in closed position, as shown in Figs. 3 and 4. The points at which the parts engage are indicated by the numeral 12.

The tongue 11b of the toggle part is formed with approximately straight parallel side bars 11g fitting between the side bars 10a of the body member, spring loops 11h embracing the body 10 side bars 10a, and a curved end 11k adapted to enter the mouth of loop 10b. The tongue end is curved upward at the end to grip the fabric to the upper side of the body loop 10b, as shown in Fig. 4.

At the upper end an attaching ring 13 is provided, being hinged by its inturned ends 13a to the upper curled end 11e of the plate 11a. A length of elastic band 14 and cloth tapes 15 may be provided for securing the clasp by its ring 13 to the post of a bed or other suitable anchorage.

The spring loops 11h of the tongue 11b ride upon the side bars 10a of the body member and keep the parts in proper operating position at all times, making it unnecessary to direct one part toward or into the other, as has been required with previous clasps wherein the fabric or material engaging elements were completely separable from each other. The operator is thereby enabled to devote one hand entirely to handling the fabric while the other hand alone can manipulate the clasp. The parts are so disposed that the tongue 11k approaches the loop 10b while moving approximately parallel to the side bars 10a so as to push the fabric F, which is shown in dotted lines, fairly through the loop. Further movement of the tongue is in an upward direction as the upper sides of the spring loops 11h engage the upper surface of the bars 10a and this clamps the fabric against the upper side of the loop as the hinged center of the toggle moves past dead center position to the final locking position.

Both the loops 11h and the loop 10b are resilient so that the fabric is resiliently locked in the clasp and the toggle is resiliently locked in dead center position so as to avoid accidental release.

The plate 11a of the toggle is accessible from both sides for the fingers and thumb of the operator. The space between the bars 10a is wide enough for the thumb or finger to easily pass through for either clamping or releasing the clasp. When the parts are in the fully opened

position as shown in Figs. 1 and 2 the end of the tongue 11k is spaced far enough away from the loop 10b to permit the finger or thumb of the operator to pass clearly through with the 5 fabric, even where several thicknesses of sheets or blankets are to be secured. Either the edge or a fold F¹ of the fabric may be pushed through the opening. The tongue member 11b is open, being made as a frame, so that the nails of the 10 thumb and finger will stand clear and not be injured during manipulation of the clasp. The thumb and fingers are not near parts which snap together when the toggle is thrown over to locking position and injury from this cause is also 15 avoided.

In operation, the thumb and index finger of one hand are placed on the plate 11a, the thumb being on top and the finger being underneath. The ends of the thumb and finger may extend 20 over the lower end of the plate within the tongue member 11b. The index finger of the other hand is placed beneath the fabric to be clasped and pushes the fabric through the opening between the tongue 11k and loop 10b, as shown in Figs. 1 25 and 2. Then the toggle plate is pressed down by the thumb as the finger is withdrawn from the opening, thus leaving a portion of the fabric between the end of the tongue and the opening of the loop 10b. Further pressure on the plate forces 30 the toggle knuckle through the opening between the side bars 10a and this causes the tongue to push a fold of the fabric through the loop and bind it against the upper edge of the loop, as shown in Figs. 3 and 4. As thus secured, the 35 fabric is firmly held and will effectively resist attempts to pull it out, particularly since the hemmed edge of the fabric must pass the clamping parts of the clasp before release can be effected.

40 In this clamping action the tongue is self threading as the loops 11h slide down the side bars 10a.

For release, the toggle is snapped back to the Fig. 2 position, whereupon the fabric may be 45 readily pulled out.

It is thus seen that the invention provides a very simple, inexpensive, easily manipulated clasp which very securely holds the material to which it is attached. The parts are always in proper 50 assembly for operation. The clasp is not likely to pinch the fingers or injure the nails of the operator. The clasp is very thin when closed to clamping position and has few projections and is unlikely to injure the infant under the covers. Such projections as are present are broad and 55 round. The grip is over sufficient area to avoid tearing the fabric. Other advantages, uses and features of the clasp will be apparent from the above description of a specific embodiment.

60 While one embodiment has been described in detail in order to illustrate the principles of the invention, it is to be understood that the invention may have various embodiments within the limits of the prior art and the scope of the subjoined claims.

65 We claim:

1. A clasp for fabrics or the like, comprising in

combination, a body member having parallel sides and a bent loop at one end, a toggle hinged at one end to the end of the body member opposite the loop, the toggle having a tongue adapted to enter said loop carrying a thickness of fabric with it, and means on the toggle near the tongue slidably embracing the sides of the body member for guiding the tongue in and out of the loop. 5

2. A clasp for fabrics or the like, comprising in combination, a body member having side bars 10 and a bent loop at the lower end, and a toggle comprising a finger plate and a frame-like tongue member, the plate being hinged at its upper end to the upper end of the body member and being hinged at its other end to the upper end of the 15 tongue member, an upwardly bent tongue at the end of the tongue member, and spring loops on the tongue member near the tongue slidably embracing the side bars of the body member. 10

3. A clasp for fabrics or the like, comprising in combination, a body member having parallel side bars and a bent loop at the lower end, and a toggle comprising a thumb plate and a frame-like tongue member, the plate being hinged to the upper end of the body member, the tongue 20 member having a tongue at its lower end adapted to enter the loop and having spring loops near the tongue slidably embracing the side bars of the body member, the knuckle of the toggle being sufficiently narrow to swing through the opening 25 between the side bars of the body member between open and closed position, and said thumb plate being of a width near its upper end to engage the side bars to stop the movement of the 30 toggle in locking position. 35

4. A clasp for fabrics or the like, comprising in combination, a body member having approximately straight parallel side bars, a downturned jaw element at its lower end and upturned 40 reversely bent portion at its upper end, and a toggle hinged to the upturned body member portion at its upper end, having spring loops slidably and retainably mounted on the side bars near its lower end, and having a jaw element at its lower end cooperating with the jaw element of the body 45 member. 45

5. A clasp for fabrics or the like, comprising in combination, a frame-like body member having side bars and a jaw element at its lower end, and a toggle hinged at its upper end to the upper 50 end of said body member, having a jaw element at its lower end, and having means for slidably and retainably connecting it near the lower end at all times to the side bars of the body member. 50

6. A clasp for fabrics or the like, comprising in combination, a frame-like body member having side bars and a jaw element at its lower end, and a toggle hinged at its upper end to the upper 55 end of said body member, having a jaw element at its lower end, and having means for slidably and retainably connecting it near the lower end at all times to the side bars of the body member, said body member and toggle being provided with interengaging elements which limit the toggle movement in locking direction. 60
